LIQUID CONTROL MEANS FOR AIR CONDITIONING APPARATUS

Charles R. Neeson, New Rochelle, N. Y., assignor to Baldwin-Southwark Corporation, a corporation of Delaware

Application July 15, 1933, Serial No. 680,642

13 Claims. (Cl. 62—129)

This invention relates generally to air conditioning apparatus and more particularly to improved means for disposing of condensed moisture on an evaporator used in the refrigerating system of this apparatus.

It is of course well-known that in air conditioning equipment a considerable amount of moisture may be extracted from the room air which is constantly circulated over the evaporator, this moisture condensing upon the evaporator to drip therefrom. It is not only desirable to collect the dripping water but also to dispose of the same in a highly efficient manner. This is particularly true in self-contained room cooler units of the type employing an air cooled condenser, such a type being shown in my Patent 2,081,553. In such an air cooled condenser system, it is desirable to have the condensate effectively discharged into the stream of condenser air to be conveyed away thereby. It is also desirable to have this water sprayed, so to speak, over the surface of the condenser so as to obtain, as far as possible, evaporation of the moisture by the heated condenser, thereby supplementing the cooling action of the air which preferably is drawn from the outside, passed over the condenser, and discharged back to the outside.

It is one object of my invention to accomplish the foregoing results by improved means whereby air is used in a positive manner in the discharge of liquid into the air stream. Another object is to provide improved means whereby the normal circulation of air through the self-contained air conditioning unit, preferably of the room unit type, is used in an improved manner to effect discharge of the condensate from a suitable tray or other receptacle.

A further object is to provide improved means whereby flow of air directly assists in effecting displacement of liquid from its normal level in the receptacle while more specifically it is an object of my invention to provide means whereby this air flow causes liquid in the receptacle to be agitated and preferably to have the liquid broken up into relatively small particles during such agitation. Another object in this respect is to provide an improved combination whereby the agitated or displaced liquid in the tray may be effectively picked up by an air stream flowing adjacent to said agitation but offset therefrom.

In one specific aspect of the invention I provide a receptacle having a plurality of openings through which air may flow upwardly, and over one of which is disposed a shield or deflector

preferably an inverted half circle or of substantially equivalent form for redirecting the upward flow of air downwardly into the condensate within the receptacle thereby to cause the redirected air to blow the condensate forcibly into the free upward flow of air passing through the adjacent opening in the receptacle.

Another object is to provide an improved arrangement and location of said air reversing deflectors whereby the liquid in the trays will be effectively disposed of even though the unit or trays may not be perfectly level, thus causing liquid to run toward one end of the tray or the other. While I have specifically shown my deflectors as extending for the full length of the trays, yet it will be understood that short lengths of the deflectors may be disposed over various openings of the trays either along one line of openings or over a series of openings in staggered relation. I preferably provide said deflector as a solid imperforate member, although if desired various small openings may be provided therein or the lower down-turned edge or edges of the deflector may be jagged, but in a more specific aspect of the invention I have supplemented the imperforate deflector with a screen which overlies the deflector preferably in slightly spaced relation thereto and with the edges of such screen disposed preferably below the normal liquid level in the receptacle whereby air blowing outwardly beneath the lower edges of the deflector will pass upwardly partially through the screen, thereby breaking up the liquid into smaller drops. These relatively small drops which simulate a spray may be easily evaporated upon engaging the condenser.

Another object is to provide an improved system of condensate collecting and disposal means having any or all of the foregoing characteristics adapted to be used either when the air conditioning apparatus is used as a room heater or room cooler, such as disclosed in Galson Patent 2,052,561, wherein the direction of refrigerant flow through the heat exchange elements may be reversed to cause the room air to circulate over what would now be the condenser and the outside air to circulate over what would now be the evaporator. In this event moisture condensed from the outside air flows over to the tray beneath the other heat exchange element and is discharged upwardly against the hot surface thereof to be evaporated and carried into the room air to humidify the same.

Other objects and advantages will be more apparent to those skilled in the art from the follow-

ing description of the accompanying drawings in which:

Fig. 1 is a vertical transverse section through a room unit embodying my invention;

5 Fig. 2 is an enlarged partial perspective of a condensate receptacle showing in vertical section the action of my improved deflector;

10 Fig. 3 is a vertical longitudinal section taken substantially on the line 3-3 of Fig. 2 and showing one manner of supporting the deflector on the tray;

Fig. 4 is a modified form of the deflector employing what might be termed a splitter;

15 Fig. 5 is a plan view of the trays beneath the condenser and evaporator taken substantially on the line 5-5 of Fig. 1;

Fig. 6 is a vertical longitudinal section taken substantially on the line 6-6 of Fig. 1;

Fig. 7 is a further modification of the deflector.

20 In the illustrated embodiments of my invention which are shown herein merely for the purpose of disclosing certain specific forms among others that the invention might take, I employ preferably a self-contained air conditioning room unit having any suitable refrigerating system including a compressor not shown and a pair of complementary heat exchange elements 1 and 2. The unit will herein be described primarily as a room cooler unit wherein the heat exchange element 1 functions as the evaporator and element 2 as the condenser, although it will of course be understood that these functions are interchanged when the unit serves as a heater. Air from a given source, such as a room, is normally circulated preferably 25 in a vertical direction over the evaporator 1 by suitable blower mechanism generally indicated at 3 while outside air is conducted through any suitable opening in the wall of the room such as a window and thence flows inwardly of the unit 30 wherein the air is discharged upwardly by a blower 4 over the condenser 2 and thence discharged away from the room through a suitable duct to the outside. The outside flow of air preferably has twice the volume and velocity over 35 the condenser 2 that the room air has over the evaporator 1. However, this does not affect the mode of operation of my improved condensate control means which herein specifically comprises trays 5 and 6 disposed beneath the condenser and evaporator preferably in relatively close relation 40 thereto.

45 The trays 5 and 6 as shown in Fig. 2 comprise preferably a series of troughs 7 disposed substantially parallel to each other and having air passages 8 therebetween. The edges 9 of the tray may be suitably secured to the walls of the air passages either by soldering or brackets. These troughs or depressions may be interconnected at certain longitudinal intervals as by cross-pieces 10, thereby providing preferably a series of short 50 lengths of air openings 8 although as shown in my other applications, these openings may if desired be continuous from end to end of the trays or they may be localized in one area as by providing a 55 circular trough.

60 The moisture in the room air which condenses on the evaporator 1 drips downwardly into the series of troughs 7 and the air flows upwardly through passages 8. The water that accumulates in tray 5 then flows over into tray 6 which receives the condensate from the evaporator through any suitable interconnecting pipe or passage 11, Fig. 5. The tray 6 is constructed identically to the one shown in Fig. 2 and both sets of 65 trays are provided specifically with two sets of

deflectors 12 and 13. These deflectors as shown in Fig. 2 are preferably of inverted curved form and spaced slightly from the open top of the passage over which they are disposed, thereby causing the air flowing upwardly through such passage to be 5 redirected downwardly into the adjacent trough 7. It will be noted that the lower edge of the deflector 12 is disposed slightly below a normal liquid level in the tray and has the effect of causing the water to build up as at 13 against one wall of 10 the adjacent opening 8. The continual flow of air downwardly into this water will force the same into the flow of air through the adjacent opening 8. The uncovered one of passages 8 has of course 15 an entraining action for all water that might flow over its top edge but this entraining action is considerably augmented by the improved deflector arrangement. In addition to increasing this entraining action, the redirected air breaks up the water into drops, thus permitting it to be more 20 effectively entrained in the upward flow of air. However, to effect even greater breaking up of the water so as to more nearly simulate a fine spraying action, there is provided a screen generally indicated at 14 of inverted semi-cylindrical 25 form secured at its top to the deflector 12 while the lower portions of the screen are preferably slightly spaced from the wall of the deflector and the ends of the screen project preferably at least on a level with the lower edge of the deflector 12, 30 although if desired the edges of the screen may project below the edges of the deflector. As a result of this screen, the air tends to force the water not only outwardly around the lower edge of the deflector and screen but also upwardly between 35 the deflector and screen, thereby breaking the water up into very small drops which may be easily entrained in the upward flow of air. This is particularly desirable especially when disposed immediately below the air cooled condenser 2 as the 40 spray tends to effectively cool the condenser in addition to the air cooling as the heat of the condenser is adapted to transform the small drops into vapor, thereby obtaining the cooling action 45 of the heated vaporization of the liquid which is not ordinarily possible in usual water cooled condensers.

As shown in Fig. 3, the deflector 12 may be supported in any suitable manner such as by a series of brackets 13 soldered or otherwise suitably secured to the raised portion 10 of the tray. This bracket serves not only as a support for the deflector 12 but also as a means of insuring proper spacing thereof.

As also shown in Fig. 5 the deflectors 12, and 55 their cooperating screens if so desired, extend preferably for the full length of the tray, although if desired these deflectors may be made in short lengths and disposed over various of the openings 8. In any event, it is seen that even though the 60 tray may not be exactly level so that water might accumulate in one end or the other of the tray, my improved deflector will cause efficient discharge of the liquid from the tray. Of course, any liquid that might be thrown upwardly against 65 the evaporator 1 will immediately drop back due to the cold surface of the evaporator but liquid thrown against the condenser will be vaporized or otherwise carried out, thereby causing the liquid from the evaporator tray to flow over through pipe 70 11 into the condenser tray 6 and thereby to be discharged to the outside air.

In the modification shown in Fig. 4, the deflector comprises two semi-cylindrical members 15 and 16 with their adjacent edges secured together 75

to provide a splitter 17. This deflector is disposed longitudinally over any one or a series of the air passages 8 with the splitter 17 preferably on the center line thereof, although if desired a one side deflector 18 may be employed as shown in Fig. 7.

It will be noted that the deflector 13 as shown in Fig. 1 is disposed over the middle one of three adjacent air passages 8 while the deflector 12 is disposed over the air passage adjacent one side 10 of the trough, thereby providing only the center free air passage 8 for taking care of the water forced out. This arrangement has the advantage of insuring even distribution of the spray thrown upwardly from the trays by the deflectors.

From the foregoing disclosure it is seen that I have provided a relatively simple and yet highly effective means for insuring proper collecting and disposal of the condensed moisture and that this improved arrangement permits a relatively small 20 volume of air flow and air velocity to carry away the condensate whether the same be blown against the hot evaporator or discharged directly to the outside. Also it is seen that my improved arrangement may be employed with either one 25 or two of the heat exchange elements.

It will of course be understood by those skilled in the art that various changes may be made in the details of construction and arrangement of parts without departing from the spirit of the 30 invention as set forth in the appended claims.

I claim:

1. Air conditioning apparatus comprising, in combination, an evaporator, means for circulating air thereover from a given source, a liquid 35 receptacle for receiving condensate from said evaporator and having air openings therethrough, means whereby air is circulated through said openings and is then discharged away from said source of air, and means for redirecting flow 40 of air through said openings downwardly into the liquid portion of said receptacle to agitate the liquid therein and cause it to be carried away in the flow of said air.

2. Air conditioning apparatus comprising, in 45 combination, an evaporator, means for circulating air thereover from a given source, a liquid tray having a series of openings therethrough, means for accumulating condensate from said evaporator and transferring it to said tray, means 50 whereby air is circulated upwardly through said openings and then discharged out of communication with said source of air, and a deflector over one of said openings for redirecting the air flow therethrough downwardly into the liquid in 55 said tray to force the liquid into the path of air flowing upwardly through an adjacent opening.

3. Air conditioning apparatus comprising, in 60 combination, an evaporator, means for circulating air thereover from a given source, a liquid receptacle for receiving condensate from said evaporator and having a plurality of openings placed side by side with a liquid trough therebetween, means for forcefully circulating air upwardly through said openings and discharging 65 the air to a point out of communication with said air source, and a deflector disposed over one of said openings and projecting into said trough whereby air is redirected downwardly into said trough to displace liquid therein and permit the 70 displaced liquid to be carried away by the upwardly flowing air through said openings.

4. Air conditioning apparatus comprising, in 75 combination, an evaporator, means for circulating air thereover from a given source, a tray for receiving condensate from said evaporator and

having a series of substantially parallel openings with a trough therebetween, means for forcefully circulating air upwardly through said openings and discharging the air to a point out of communication with said air source, and a deflector disposed over one of said openings in spaced relation to the top thereof whereby air is directed laterally with respect to said opening to effect agitation of liquid in said trough. 5

5. Air conditioning apparatus comprising, in 10 combination, an evaporator, means for circulating air thereover from a given source, a tray for receiving condensate from said evaporator and having a series of openings therein and a liquid trough between said openings, means for forcefully circulating air upwardly through said openings and discharging the air to a point out of communication with said air source, and an inverted curved deflector disposed over one of said 15 openings with one edge of the deflector extending downwardly below the normal liquid level in said trough.

6. Air conditioning apparatus comprising, in combination, an evaporator, means for circulating air thereover from a given source, a receptacle for receiving condensate from said evaporator and having a series of openings therethrough with a liquid trough on each side of each opening, an inverted deflector disposed over one of said openings in spaced relation to the top 25 thereof and the edges of said deflector being disposed in said adjacent troughs, means for forcefully circulating air upwardly through said opening whereby the air is directed downwardly into said troughs to agitate liquid therein, and means 30 for discharging said latter air flow to a point out of communication with said given air source. 35

7. Air conditioning apparatus comprising, in combination, an evaporator, means for circulating air thereover from a given source, a receptacle for receiving condensate from said evaporator and having a series of openings therethrough with a liquid trough on each side of each opening, an inverted deflector disposed over 40 one of said openings in spaced relation to the top thereof and the edges of said deflector being disposed in said adjacent troughs, means for forcefully circulating air upwardly through said opening whereby the air is directed downwardly into said troughs to agitate liquid therein, other 45 of said openings being free and unrestricted to permit a straight upward flow of air therethrough thereby to entrain the agitated liquid in the adjacent trough, and means for discharging said latter air flow to a point out of communication with said given air source. 50

8. Air conditioning apparatus comprising, in combination, an evaporator, means for circulating air thereover from a given source, a tray for receiving condensate from said evaporator and 60 having a plurality of substantially parallel openings therethrough with liquid troughs therebetween, a deflector disposed over certain of said openings at opposite ends of said receptacle for redirecting air flow into adjacent troughs while 65 others of said openings are free and unrestricted, means for forcibly circulating air through all of said openings whereby said deflectors cause a portion of said air to agitate the liquid in said adjacent troughs, and means for discharging the 70 flow of air through said openings to a point out of communication with said given air source.

9. Air conditioning apparatus comprising, in combination, an evaporator, means for circulating air thereover from a given source, a receptacle 75

for receiving condensate from said evaporator and having an air passage therethrough and a trough adjacent the same, a deflector for redirecting the air downwardly into said trough, a 5 screen disposed adjacent said deflector to permit air and water to pass therethrough, and means for forcibly circulating air through said passage and then discharging the air to a point out of communication with said given air source, where- 10 by the liquid in said trough is agitated by the air flow through said passage and broken up as it passes through said screen.

10. Air conditioning apparatus comprising, in combination, an evaporator, means for circulating air thereover from a given source, a receptacle 15 for receiving condensate from said evaporator and having a vertical opening therethrough and liquid troughs on each side thereof, a deflector disposed over said opening for directing air 20 downwardly into each of said troughs, a screen disposed over said deflector and in at least partial spaced relation thereto, and means for forcefully circulating air through said opening and then discharging air to a point out of commun- 25 cation with said given source, said air in flowing under the lower edge of said deflector passing partly through said screen to carry water therewith.

11. Air conditioning apparatus comprising, in 30 combination, an evaporator, means for circulating air thereover from a given source, a receptacle for receiving condensate from said evaporator and having a vertical opening therethrough and liquid troughs on each side thereof, means for 35 forcefully circulating air through said opening

and discharging such air to a point different from that to which air passing over the evaporator is discharged, a semi-cylindrical deflector disposed over said opening for directing said air flow therethrough downwardly into each of said troughs, a semi-cylindrical screen disposed over said deflector and in at least partial spaced relation thereto whereby air flowing under the lower edge of said deflector may pass partly through 5 said screen to carry water therewith. 10

12. Air conditioning apparatus comprising, in combination, a refrigerant condenser and evaporator, means for directing separate streams of air flow over said evaporator and condenser, a liquid tray disposed beneath said evaporator, and a second liquid tray disposed beneath said condenser and communicating with said other tray whereby liquid may flow between the same in either direction, each of said trays having openings therethrough with liquid troughs adjacent 15 20 said openings and deflectors over certain of said openings in each tray for redirecting air flow into said troughs to agitate water therein.

13. Air conditioning apparatus comprising, in combination, a condenser and evaporator, means for circulating room air over said evaporator and outside air over said condenser, means for collecting condensate from said evaporator, and means for discharging a stream of air directly 25 into the condensate in said collecting means so 30 as to forcefully atomize the condensate therein and carry the condensate away in the stream of air flowing from said circulating means.

CHARLES R. NEESON. 35
